UNITED STATES PATENT OFFICE

SOJIRO FRANK SEIBUYA, OF SAN FRANCISCO, CALIFORNIA

ANGLE TRISECTOR

Application filed July 27, 1929. Serial No. 381,507.

My invention relates to improvements in angle trisectors and it consists in the combinations, constructions and arrangements hereinafter described and claimed.

An object of my invention is to provide an improvement over that form of the device shown in my co-pending application filed January 23rd, 1929, Serial No. 384,567. In the present device, the curved edge used for determining one-third of the angle in question is graduated so as to give the proper point location for angles ranging between zero degrees to 180 degrees. This marking of the device saves considerable time in trisecting an angle.

Other objects and advantages will appear in the following specification, and the novel features of the device will be particularly pointed out in the appended claims.

My invention is illustrated in the accompanying drawing forming a part of this application, in which

Figure 1 is a plan view of the device;

Figure 2 illustrates how the trisector curve is obtained; and

Figure 3 shows how the markings on the trisector curve are obtained.

It is best to show how the device is made and how the particular trisector curve is arrived at. Referring to Figure 1, it will be noted that a protractor 1 has a radially-extending arm 2 projecting from its periphery. The edge 3 of this arm is perpendicular to the edge 4 of the protractor and is in line with the center 5 of the protractor.

A curved arm 8 projects from the protractor and terminates in the arm 2. The edge 7 of this arm extends from the sixty degree mark on the protractor and terminates on the edge 3 at the point 8. The curved edge 7 is predetermined and is obtained in a manner hereinafter described. With this curve any angle up to one hundred and eighty degrees can be trisected.

The trisector 9 shown in Figure 4 is cut out of the piece projecting from the protractor 1. The edge 10 of this piece conforms to the edge 7, and the edges 11 and 12 conform to the edges 3 and 13 of the first form.

I will now describe how the curved edge 7 is determined. In Figure 2, I draw a line A—B equal to the distance between points 14 and 15 on the trisector shown in Figure 1.

The line A—B is bisected at O and a perpendicular O—K is drawn from this point. The arc A—B is now drawn and points M and D sixty degrees apart and sixty degrees from the points A and B are located. This will leave the arc K—D equal to one-third of the arc A—K. The arc K—D is divided into a number of equal parts designated by the letter X. The drawing shows eight equal parts. In like manner, the arc A—K is divided into eight equal parts designated by the letter Y. Arc X is equal to one-third of the arc Y.

With the radius O—B and the points G as centers in the arc A—K, arcs G' are drawn. With the same radius but with the points E on the arc K—D as centers, arcs E' are drawn, these intersecting the arcs G' to form a number of points M'. A curved line M—L is now drawn through all of the points M', and this curved line is the one corresponding to the curved edges 7 and 10.

I have described how the curved edge 7 is determined. I will now show how the markings from zero to 180 degrees on the curved edge are obtained. In Figure 3, I show the periphery of the protractor 1 as having a number of lines 16 extending radially therefrom. These lines are numbered from 110 to 180 and represent various angles having equivalent numbered degrees. For example, the line 180 coincides with the edge 4 and passes through the center 5. The line 170 is placed five degrees up on the protractor and passes to the center 5 and then on through to five degrees up on the opposite side of the protractor. The angle 160 passes through the ten degree mark on one side of the protractor and through the 170 degree mark on the other side, the vertex of this angle being positioned at the center 5.

With the point 14 as a center and a radius equal to the distance between this point and the center 5, an arc 17 may be inscribed on

the curved arm 6. This arc will intersect the sixty degree mark on the protractor 1. This gives us 180 degrees, and it will be noted that Figures 1 and 3 are marked accordingly.

5 In like manner, arcs are struck from the intersection of the lines 16 with the periphery of the protractor as centers, and the resulting marks 17 on the arm 6 are numbered as shown in Figures 1 and 3.

10 From the foregoing description of the various parts of the device, the operation thereof may be readily understood.

Assuming that the angle RST, Figure 1, 15 is to be trisected. This angle is first bisected by the line JS. The device is now laid upon the angle RST to determine its number of degrees. In the present instance, I have shown an angle of sixty degrees. The 20 center 5 of the protractor is placed on the vertex 5 and the edge 3 is coincided with the line JS. A mark is made upon the sheet of paper containing the angle RST opposite the number sixty on the arm 6 and adjacent to the edge 7. This mark or point can now be connected to the vertex S by the line QS. The resulting angle RSQ is 25 one-third of the angle RST.

Although I have shown and described one 30 embodiment of my invention, it is to be understood that the same is susceptible of various changes, and I reserve the right to employ such changes as may come within the scope of the appended claims.

35 I claim:

1. A trisector for an angle having a semi-circular shaped member, a radially-extending arm projecting from said member, and a curved arm having its ends secured to the 40 semi-circular member and the free end of said radially-extending arm, the inner edge of said curved arm being shaped in a predetermined manner for use in trisecting angles, said curved arm having markings 45 thereon for indicating the proper point for trisecting the angle.

2. A device for trisecting angles comprising a protractor, a radially-extending arm extending from said protractor and having 50 one edge terminating at the ninety degree mark on the protractor, a curved arm extending from the protractor to the free end of said first-named arm, the inner edge of said curved arm starting from the sixty degree 55 mark on the protractor, said curve being prearranged for use in the trisection of an angle, said curved arm having markings thereon for indicating the proper point for trisecting the angle.
